UNITED STATES PATENT OFFICE.

ADAM MIEDEN, OF DEADWOOD, CALIFORNIA.

POCKET MEMORANDUM-BOOK.

1,025,007.

Specification of Letters Patent. Patented Apr. 30, 1912.

Application filed January 6, 1911. Serial No. 601,090.

To all whom it may concern:

Be it known that I, ADAM MIEDEN, a citizen of the United States, residing at Deadwood, in the county of Trinity and State 5 of California, have invented a new and useful Pocket Memorandum-Book, of which the following is a specification.

The invention relates to improvements in memorandum books.

10 The object of the present invention is to improve the construction of memorandum books, and to equip the same with simple, durable and inexpensive means for holding writing material and writing implements 15 and for securely retaining a memorandum book in the pocket of a garment.

A further object of the invention is to provide an efficient clip, adapted to be readily applied to the cover of a memorandum 20 book, and capable of retaining itself in position on the same and of also presenting inner and outer engaging portions, located at the inner and outer faces of the cover so as to operate both interiorly and exteriorly 25 thereof.

With these and other objects in view, the invention consists in the construction and 30 novel combination of parts hereinafter fully described, illustrated in the accompanying drawings, and pointed out in the claims hereto appended; it being understood that various changes in the form, proportion, size and minor details of construction, within the scope of the claims, may be resorted 35 to without departing from the spirit or sacrificing any of the advantages of the invention.

In the drawings:—Figure 1 is a perspective view of a memorandum book equipped 40 with clips, constructed in accordance with this invention, the book being open to show the inner engaging portions. Fig. 2 is a perspective view, the memorandum book being closed. Fig. 3 is a central longitudinal 45 sectional view, the book being closed. Fig. 4 is a sectional view on the line 4—4 of Fig. 3. Fig. 5 is a detail sectional view on the line 5—5 of Fig. 4, the lever being arranged for holding the inner portion of the 50 clip out of engagement with the tablet. Fig. 6 is a transverse sectional view on the line 6—6 of Fig. 1. Fig. 7 is a detail perspective view of the clip of one of the covers. Fig. 8 is a similar view of the clip of the 55 other cover. Figs. 9 and 10 are detail perspective views, showing other forms of the

tablet holding clip. Figs. 11 and 12 are detail perspective views, illustrating other forms of the pocket engaging clip. Fig. 13 is a detail view of the lever for operating 60 the tablet holding clip. Fig. 14 is a transverse sectional view, showing applied to a cover the clip illustrated in Fig. 10.

Like numerals of reference designate corresponding parts in all the figures of the 65 drawings.

In Figs. 1 to 8 inclusive of the accompanying drawings in which is illustrated the preferred form of the invention, 1 designates a memorandum book of any preferred 70 construction consisting of two flexibly connected covers 2 and 3. The cover 2, which forms a base or back for a tablet 4, is preferably equipped with a covering of flexible material, such as leather, cloth, or the like, 75 and it is provided with a flexible pocket 5 open at the outer end of the cover, and adapted to receive pencils, pens or similar writing implements, as clearly illustrated in Figs. 1 to 3 inclusive.

80 The cover 2 is equipped with a tablet-holding clip, comprising an inner approximately U-shaped tablet-engaging loop 6, outer pocket engaging tongues 7 and spring bends 8, connecting the tongues with the 85 sides of the tablet holding loop. The inner tablet engaging loop is composed of spaced sides and an outer connecting transverse portion, which is provided at opposite sides of the center with inwardly extending approximately V-shaped bends 9, forming spaced gripping portions for overlapping and engaging the face of the tablet 4, as 90 clearly illustrated in Fig. 1 of the drawings. The spaced side portions of the U-shaped 95 tablet-engaging loop are straight, and are located at the side edges of the leaves or sheets of the tablet and assist in retaining the tablet in proper position on the cover 2 of the memorandum book. The spring bends 100 are connected with the inner ends of the sides of the tablet engaging loop by short straight attaching portions 10, which pierce the cover 2, the inner tablet engaging loop being located at the inner face of the cover 105 2, and the tongues being arranged at the outer face of the same. The spring bends 8 are preferably concealed within or beneath the covering of the cover 2, but they may be arranged on the exterior of the same if desired. Each transverse spring bend consists 110 of inner and outer straight transverse por-

tions 11 and 12, a straight intermediate connecting portion 13, and an outwardly extending arm 14. The straight connecting intermediate portion 13 connects the adjacent ends of the transverse portions 11 and 12, and the arms 14, which are straight, extend outwardly from the said terminals of the portions 11 of the spring bends and offset the inner ends of the tongue 7 from the plane of their outer engaging ends 15. The tongues 7 are arranged at an angle to the plane of the cover 2, and they pierce the outer wall of the pocket 5 and engage the exterior of the same at spaced points and 15 sub-divide the pocket into separate portions for holding pencils, fountain pens, etc. The tongues, which are resilient, also yieldably maintain the outer wall of the pocket in engagement with the writing implements and 20 thereby securely hold the same in the subdivisions of the pocket 5. The terminals 15 of the resilient tongues are bent on themselves to form eyes to provide blunt ends to prevent the ends of the tongues from piercing the outer wall of the pocket. The angular spring bends support the inclined or angularly disposed tongues in proper position for engaging the flexible outer wall of the pocket, and they also operate to dis- 25 tribute the strain over a considerable portion of the steel wire, or other material of which the clip is constructed, whereby the durability of the clip is materially increased.

In order to facilitate placing the tablet 4 in the clip, the memorandum book is equipped with a lever 16, provided at one end with an integral pivot 17 and provided at the other end with an operating arm 18 and having an eye 19, arranged adjacent to 40 the operating arm and receiving the transverse portion of the tablet engaging loop and slidably on the same between the V-shaped bends 9. The pivot 17, which extends in the opposite direction from the operating arm 18, is suitably mounted in the cover 2, which is provided at one side of the lever with a shoulder 20, arranged to permit the lever to swing slightly beyond the center, so that the resiliency of the tablet- 45 engaging clip will maintain the lever in engagement with the shoulder and thereby enable the lever to hold the clip in its open position until it is swung back beyond the center.

50 In Fig. 9 of the drawings, is illustrated a simpler form of the tablet and pencil holding clip, the inclined or angularly related tongues 21 being connected with the sides 22 of the tablet engaging loop by straight transverse portions 23 and outwardly projecting arms 24, short straight transverse attaching portions 23^a being provided. In Fig. 10 is illustrated another form of tablet engaging clip in which the tablet engaging loop 25, the transverse connecting portions

26, the outwardly projecting arms 27 and the short straight attaching portions 26^a are constructed similar to the corresponding parts illustrated in Fig. 9. The clip of Fig. 10 is equipped with a pair of inclined or angularly disposed approximately U-shaped tongues 28, spaced apart and having spaced side portions and adapted to sub-divide a pocket into five divisions for the reception of five different pencils or other writing implements. The pocket, however, may be divided into any number of subdivisions by employing a proper number of spaced inclined tongues. 75

In each form of the invention the tablet 80 engaging clip retains itself on the cover of the memorandum book, and in addition thereto performs the double function of holding the tablet and retaining the writing implements in the pocket of the memorandum book. The other cover of the memorandum book is equipped with a clip consisting of an inner approximately rectangular resilient clamping loop 29 and an exterior jaw or tongue 30. The inner clamping loop, 85 which has one end free, is adapted to hold a stamp book, cards and various other miscellaneous papers, and the exterior tongue or jaw is adapted to engage the fabric of the pocket of a garment to retain the memorandum book therein. The rectangular loop 29 has an exterior U-shaped clamping portion, and inner angular spring bends 31 consisting of spaced transverse portions 32 and 33, and a straight intermediate connecting portion 34, arranged at right angles to the transverse portions 32 and 33. In practice the spring bends will be concealed within the covering of the cover 3, but this is not absolutely necessary. The spring bends are 90 adapted to distribute the strain throughout a considerable portion of the steel wire, or other material of the clip and increase the durability thereof. The inner transverse portion 33 is connected by a short attaching portion 35 with an approximately U-shaped loop 36, which supports the tongue or jaw 30. The attaching portion 35 pierces the cover 3 of the book, and it connects the inner and outer portions of the clip with each other. The U-shaped loop 36 is preferably arranged beneath the covering of the cover, and the tongue or jaw 30, which is formed by doubling the wire on itself, is inclined or angularly disposed and is connected with the loop by an outwardly projecting arm 37 and has an angularly bent terminal engaging portion 38. The outer side of the loop 36 is provided with a laterally projecting gripping device, adapted to engage one of the side edges of the cover and consists of an outwardly extending transverse portion 39, a short longitudinal connecting portion 40, an inwardly extending transverse portion 41 and a longitudinal

100 portion 42. The outer side of the loop 36 is provided with a laterally projecting gripping device, adapted to engage one of the side edges of the cover and consists of an outwardly extending transverse portion 39, a short longitudinal connecting portion 40, an inwardly extending transverse portion 41 and a longitudinal

terminal portion 42, arranged in substantial parallelism with the longitudinal connecting portion 40 and being of a length slightly in excess of the same. The gripping of the 5 side edge of the cover 3 by the said laterally projecting gripping device assists in retaining the clip in proper position on the same. The clip retains itself in position on the cover and also performs the double function of engaging the pocket of a garment 10 and holding miscellaneous articles.

In Fig. 11 of the drawings, is illustrated a clip differing slightly in form from the clip of the cover 3, the rectangular loop 43 being provided at the outer portion of the 15 angular spring bends 44 with a short fastening portion 45, which is adapted to pierce the cover adjacent to the side edges thereof instead of near the central portion of the 20 same. The fastening portion 45 is connected with the outer side of the loop 43 with a short transverse connection portion 46, and the inner terminal of the angularly bent resilient connecting portion 44 is connected 25 directly with the inner side of the U-shaped loop 47, which supports the pocket engaging jaw or tongue 48. The outer side of the loop 47 is provided with a cover engaging device 49, constructed similar to that 30 heretofore described, and adapted to engage the side edge of the cover.

In Fig. 12 of the drawings, is illustrated a pocket engaging device consisting of a tongue 50, a supporting loop 51 and a cover 35 engaging device 52, adapted to grip the side edge of the cover. The loop 51, which is approximately U-shaped, is provided at the opposite side with an attaching device 53, having a short angularly bent portion 54 to pierce the cover and provided with a 40 relatively small approximately V-shaped loop 55, connected with the attaching portion 54 by a short transverse portion 56, and adapted to engage the opposite face of 45 the cover. The form of clip shown in Fig. 12 is adapted to be applied to any memorandum book, when it is merely desired to equip the same with means for retaining the book in the pocket of a garment.

50 The clips with their inner and outer engaging portions when applied to the covers of a memorandum book or analogous book are adapted to permit any one of the engaging portions to be manipulated without affecting or disturbing the other engaging portions, or the articles held by the same.

Having thus fully described my invention, what I claim as new and desire to 60 secure by Letters Patent, is:—

1. A memorandum book provided with a clip mounted on the cover and including inner and outer resilient clamping portions located at the inner and outer faces of the 65 cover, and an attaching portion located in-

teriorly of the cover and connecting the inner and outer clamping portions.

2. A memorandum book provided with a clip mounted on the cover and constructed of a single piece of resilient material and 70 consisting of inner and outer resilient clamping portions located at the inner and outer faces of the cover, and an intermediate attaching portion piercing the cover and connecting the inner and outer clamping 75 portions.

3. A memorandum book provided with a clip mounted on the cover and including an approximately U-shaped loop located at the inner face of the cover, a resilient tongue 80 operating at the opposite face of the cover, and an intermediate attaching portion piercing the cover and connecting the loop and the tongue.

4. A memorandum book provided with a 85 clip mounted on the cover and including an approximately U-shaped clamping loop located at the inner face of the cover, a resilient clamping tongue located at the opposite face of the cover, and a connecting portion 90 provided with an outwardly projecting arm connected with the tongue and supporting the latter in an angular position with relation to the plane of the cover.

5. A memorandum book provided with a 95 clip mounted on the cover and including an approximately U-shaped clamping loop located at the inner face of the cover, a resilient clamping tongue operating at the opposite face of the cover, and an angularly bent 100 portion connecting the loop and the tongue and forming a plurality of spring bends.

6. A memorandum book provided with a clip mounted on the cover and including a clamping loop located at the inner face of 105 the cover, a resilient clamping tongue operating at the opposite face of the cover, and an angularly bent portion connecting the tongue and the loop and forming a plurality of spring bends and provided with an 110 outwardly projecting arm supporting the tongue in angular position with relation to the plane of the cover.

7. A memorandum book provided with a clip mounted on the cover and including 115 an approximately U-shaped clamping loop having spaced sides, a pair of resilient clamping tongues, and intermediate portions connecting the tongue with the sides of the loop and piercing the cover to permit the loop and the tongue to operate at opposite faces of the said cover.

8. A memorandum book provided with a clip mounted on the cover and including an approximately U-shaped resilient tablet- 125 clamping loop composed of spaced sides and a transverse connecting portion provided with spaced inwardly extending bends forming gripping portions for engaging the tablet.

9. A memorandum book provided with a clip mounted on the cover and including a resilient clamping portion, and a pivoted lever extending from the clip to the cover and arranged to swing to a position to hold the resilient clamping portion of the clip spaced from the cover of the book. 5
10. A memorandum book provided with a clip mounted on the cover and including a resilient clamping portion, and a pivoted lever extending from the clip to the cover and having an eye slidable on the clamping portion of the clip, said lever being arranged to swing to a position to hold the clip spaced from the cover. 10
11. A memorandum book provided with a clip mounted on the cover and including a resilient clamping portion, and a lever pivoted at one end and provided at the other end with operating means slidably connected at an intermediate point with the clamping portion of the clip and adapted to hold the same spaced from the cover. 15
12. The combination with a memorandum book provided with a cover having an exterior flexible pocket, of a clip including a plurality of spaced resilient clamping tongues engaging the outer wall of the pocket and sub-dividing the same and adapted to hold the said outer wall yieldably in engagement with writing implements in said pocket. 20
13. The combination with a memorandum book provided with a cover having an exterior flexible pocket, of a clip having a plurality of spaced resilient clamping tongues extending along the outer wall of the pocket and piercing the same, the terminal portions of the tongues being located exteriorly of the outer wall of the pocket and engaging the same to sub-divide the pocket and to yieldably hold the said outer wall in engagement with writing implements in said pocket. 25
14. A memorandum book provided with a clip mounted on the cover and including a clamping loop located at the inner face of the cover, a garment-clamping tongue arranged at the outer face of the cover and co-acting therewith for securing the memorandum book in a pocket of a garment, and an intermediate attaching portion connecting the loop and the tongue. 30
15. A memorandum book provided with a clip mounted on the cover and including an approximately U-shaped loop located at the inner face of the cover and having one end free, a garment clamping tongue arranged at the outer face of the cover and co-acting therewith to secure the memorandum book in a pocket of a garment, and an intermediate portion connecting the other end of the inner loop with the tongue. 35
16. A memorandum book provided with a clip mounted on the cover of the book and including an approximately U-shaped loop located at the inner face of the cover and having one end free, a resilient tongue located at the outer face of the cover and co-acting therewith to clamp a garment for securing the memorandum book in a pocket thereof, and an intermediate portion connecting the tongue with the other end of the said loop and provided with a plurality of spring bends. 40
17. A memorandum book provided with a clip including a resilient clamping tongue arranged at the outer face of the cover and co-acting therewith to engage a garment to retain the memorandum book in a pocket thereof, and an approximately U-shaped loop located at the inner face of the cover and connected with and supporting the tongue and provided at opposite side edges of the cover with means for holding the clip on the same. 45
18. A memorandum book provided with a clip including a clamping tongue arranged on the outer face of the cover and co-acting therewith to engage a garment to secure the memorandum book in a pocket thereof, a loop connected with the clamping tongue and arranged at the inner face of the cover and provided with a cover engaging device having a portion arranged to embrace and engage the cover at one of the side edges thereof. 50
19. A memorandum book provided with a clip including a clamping tongue arranged on the outer face of the cover and co-acting therewith to clamp a garment, a loop connected with the clamping tongue and arranged at the inner face of the cover and provided with a cover engaging device consisting of spaced transverse portions to fit against the outer face of the cover, and a longitudinal portion arranged to extend along the side edge of the cover and connecting the said transverse portions. 55
20. A memorandum book provided with a clip including a clamping tongue arranged on the outer face of the cover and co-acting therewith to clamp a garment, a loop connected with the clamping tongue and arranged at the inner face of the cover and provided with a cover engaging device consisting of spaced transverse portions to fit against the opposite face of the cover, and a longitudinal portion arranged to extend along the side edge of the cover and connecting the said transverse portions, and a terminal longitudinal portion extending from the inner end of one of the transverse portions and arranged in substantial parallelism with the longitudinal connecting portion. 60
21. A memorandum book provided with a clip including an approximately U-shaped loop arranged at the inner face of one cover and having one end free, a resilient tongue located at the outer face of the cover, an ap- 65

proximately U-shaped device connected with and supporting the tongue, an angularly bent portion connecting one side of the supporting device with the other end of the inner loop, and a cover-engaging device located at the other side of the supporting loop and having portions arranged to embrace and engage the side edge of the cover.

22. A memorandum book provided with
10 a clip constructed of a single piece of re-
silient material and including a resilient
clamping loop located at the inner face of
the cover and co-acting therewith to clamp a
garment, a resilient clamping tongue ar-
15 ranged at the outer face of the cover and
formed by doubling the material to form

two sides, a supporting loop connected with
the sides of the tongue, an intermediate por-
tion piercing the cover and connecting one
side of the supporting loop with one side of
the inner clamping loop, and a cover-engag-
ing device connected with the other side of
the supporting loop and having portions ar-
ranged to engage the cover at the adjacent
side edge thereof. 20

In testimony, that I claim the foregoing as
my own, I have hereto affixed my signature
in the presence of two witnesses.

ADAM MIEDEN.
